UNITED STATES PATENT OFFICE

2,514,498

ELEVATOR STRUCTURE

Adrian John Kesler, Burke, Idaho, assignor of
one-half to Frederick W. Kesler, Soda Springs,
Idaho

Application November 10, 1948, Serial No. 59,259

2 Claims. (Cl. 187—19)

1

This invention relates to a novel elevator structure particularly adapted for use in mines and employing a novel rack and pinion means in lieu of cables for supporting an elevator for movement in an elevator shaft.

More particularly, it is an object of the present invention to provide an elevator structure which will eliminate the use of cables and the danger of breakage adherent in the use thereof and by means of which an elevator may be safely supported for movement in an elevator shaft by a means which will not be subject to releasing the elevator due to a breakage.

More particularly, it is an object of the present invention to provide a double rack and pinion means by means of which an elevator is supported for movement in either direction in a shaft and which is so constructed as to eliminate all angular thrust on the rack and pinion connection for minimizing wear and the danger of breakage and for securely maintaining the racks and pinions thereof in proper meshing engagement.

Various other objects and advantages of the invention will hereinafter become more fully apparent from the following description of the drawings, illustrating a presently preferred embodiment thereof, and wherein:

Figure 1 is a cross sectional view of an elevator shaft showing an elevator in top plan disposed therein and taken substantially along a plane as indicated by the line 1—1 of Figure 2;

Figure 2 is a vertical sectional view of the elevator and a portion of the elevator shaft taken substantially along a plane as indicated by the line 2—2 of Figure 1, and

Figures 3 and 4 are vertical sectional views taken substantially along planes as indicated by the lines 3—3 and 4—4 of Figure 2.

Referring more specifically to the drawings, the numeral 5 designates generally an elevator shaft of substantially rectangular cross section which is lined with timber as indicated at 6 and to the opposite sides of which are secured racks 7. The racks 7, which may be secured by any suitable fastenings 8 are secured to the inner sides of the timber lining of the shaft 5 in opposed relationship to one another, said racks extending longitudinally of the shaft and being disposed in equally spaced relationship to the other sides thereof. Each rack 7 includes a base which is disposed against and secured to the shaft lining and a flange 9 which projects perpendicularly from the base, intermediate of its side edges and which extends inwardly with re-

spect to the center of the shaft 5. Each flange 9 has a corresponding rack portion 10 on each side thereof. The other two sides of the shaft lining are each provided with a pair of rails 11 and 12 which rails likewise extend longitudinally of the shaft 5 and are secured by additional fastenings 8 thereto, which fastenings likewise extend through the base portions of the rails 11 and 12. As illustrated in Figure 2, the rails 11 are preferably electrically insulated from the timber lining 6 by strips of insulating material 13.

An elevator, designated generally 14, shown disposed within the shaft 5, includes a frame 15 having a bottom or platform 15, a top frame portion 16, upright corner posts 17 and longitudinally spaced side members 18, 19 and 20 which are fastened to the corner posts 17.

For the purpose of illustrating one form of prime mover for the elevator 14, an electric motor 21 of the reversing type is shown supported on and fastened to the bottom or platform 15 and is provided with a driven shaft 22 to which is secured a small beveled gear 23 which meshes with a larger beveled gear 24 which is fixed to the lower end of a shaft 25. The shaft 25 is journaled in a bearing 26 which is secured to one of the lower side members 20 and in corresponding bearings 27 which are secured to the side members 18 and 19. The shaft 25 has a pair of worms fixed thereto, designated 28, which are disposed between the journal portions of the bearings 27 and which mesh with corresponding worm gears 29 one of which is fixed to an upper shaft 30 and the other of which is fixed to a lower shaft 31. The shafts 30 and 31 are journaled adjacent their ends in the side members 18 and 19, respectively, preferably in bearings 32 which project from the outer sides of said members.

A countershaft 33 is journaled at one end thereof in a thrust bearing portion of the bearing 26 and at its opposite end in a thrust bearing 34 which is secured to a portion of the side member 20. A beveled gear 35 which is fixed to the shaft 33 meshes with a beveled gear 36 from the shaft 25 and which is disposed above the beveled gear 35. A similar beveled gear 37 on the shaft 33 meshes with a beveled gear 38, corresponding to the beveled gear 36 and which is disposed above the gear 37 and fixed to the lower end of an upright shaft 39. The shaft 39 is journaled in a pair of bearings 21 which are mounted on the side members 18 and 19 on the opposite sides of the elevator 14 to the first

3

mentioned bearings 27 and said shaft 39 likewise has fixed thereto a pair of worms 28 which mesh with a second pair of upper and lower worm gears 29 fixed to an upper shaft 30a and a lower shaft 31a which shafts are journaled like the shafts 30 and 31 in the side members 18 and 19, respectively.

The shafts 30 and 30a at each end thereof and externally of the elevator frame structure have fixed thereto relatively large pinions 40 and 41 and the lower shafts 31 and 31a have pinions 42 and 43, respectively, secured to each of their ends and likewise externally of the elevator frame. The pinions 40, 41, 42 and 43 at corresponding ends of the shafts 30, 31, 30a and 31a engage the rack portions 10 of one of the racks 7 and the complementary pinions at the opposite ends of said shafts engage the other rack. The pinions 40 and 42 engage the rack portions 10 on one side of the flange 9 while the pinions 41 and 43 engage the rack portion 10 on the opposite side of said flange, as clearly illustrated in Figures 1 and 2.

The portions of the side members 18 and 19 to which the bearings 27 are secured also mount wheel journal brackets 40a two of which are secured to the outer side of each of said portions and each of which brackets 40a journal a flanged wheel 41a. The wheels 41a engage the rails 11 and 12 and as best illustrated in Figure 1 are disposed so that the flanges of said wheels engage the remote sides of the heads of the rails. The wheel brackets 40a carrying the wheels which engage the rails 11 are preferably insulated from the elevator by strips of electrical insulating material 13, as seen in Figure 1. An electrical conductor 42a extends from the motor 21 and is in electrical contact with one of the wheels 41a engaging one of the rails 11, which rail is adapted to carry current to the electric motor 21 from an electric source as indicated diagrammatically at 43a while the other rail 11 constitutes a ground conductor back to said electric source and is connected to the electric motor 21 by a conductor wire 44 which is electrically connected to one of the wheels 41a engaging said last mentioned rail 11. Suitable reversing control means, not shown, may be provided for the electric motor 21 to enable it to be driven in either direction and any suitable brake means as indicated at 45 in Figure 2 may be provided to hold the shaft 22 against rotation when the motor 21 is not energized to thereby prevent rotation of the shafts 25, 30, 31, 30a, 31a, 33 and 39. A coupling is shown at 46 in Figure 2 to indicate that a number of elevators can be connected in tandem within the shaft 5. It will be understood that the elevator 14 as illustrated is only intended to disclose a structure for mounting the driving means between the prime mover 21 and the racks 7 and that the size of said elevator could be varied for affording the necessary space for accommodating passengers or other loads to be carried. Furthermore, it will be readily apparent that other types of prime movers could be utilized in lieu of the electric motor 21.

From the foregoing it will be readily obvious that when the motor shaft 22 is driven in one direction that the shafts 25 and 39 will be driven in the same direction and by being disposed on the remote sides of the shafts 30, 31 and 30a, 31a will cause said shafts to be driven in opposite directions so that the pinions 40 and 42 will revolve in one direction as the pinions 41 and 43 are revolving at the same speed in the opposite

4

direction for moving the elevator 14 either upwardly or downwardly of the elevator shaft 5 due to the meshing engagement of the pinions 40, 41, 42 and 43 with the rack portions 10. It will also be readily apparent that the flanged wheels 41a being in engagement with the remote sides of the rails 11 and 12 will function to hold the elevator 14 centrally with respect to the shaft 5 during its movement and to prevent any lateral displacement of the elevator relatively to the shaft 5 in any direction to thereby insure that the pinions will be maintained in proper meshing engagement with the rack portions 10 to minimize wear on said pinions and rack portions. Thus, it will be apparent that an elevator structure has been provided wherein no cables are utilized for raising, lowering or supporting the elevator thereby eliminating the danger of accidents due to breakage of a supporting cable.

20 Various modifications and changes are contemplated and may obviously be resorted to, without departing from the spirit or scope of the invention as hereinafter defined by the appended claims.

25 I claim as my invention:

1. An elevator structure comprising an elevator shaft of substantially rectangular cross section, racks secured to two oppositely disposed sides of said shaft and extending longitudinally thereof, 30 each of said racks including an inwardly extending flange having a rack portion on each side thereof, an elevator movable longitudinally in the elevator shaft, a pair of shafts journaled in portions of the elevator and extending outwardly from opposite sides of the elevator, pinions keyed to the ends of said shafts, the pinions on corresponding ends of the shafts being disposed on opposite sides of the flange of one of said racks for meshing engagement with the rack portions thereof, a prime mover connected to each of said shafts for driving the shafts in opposite directions to cause the pinions engaging each of said racks to revolve in opposite directions for propelling the elevator either upwardly or downwardly in the elevator shaft, the other two walls of said elevator shaft having rails fixed thereto and extending longitudinally thereof, brackets supported on the elevator and externally thereof, and a rail engaging flanged wheel journaled in each of said brackets, said wheels engaging said rails for guiding the elevator in its movement in the elevator shaft.

2. An elevator structure comprising an elevator shaft of substantially rectangular cross section, racks secured to two oppositely disposed sides of said shaft and extending longitudinally thereof, each of said racks including an inwardly extending flange having a rack portion on each side thereof, an elevator movable longitudinally in the elevator shaft, a pair of shafts journaled in portions of the elevator and extending outwardly from opposite sides of the elevator, pinions keyed to the ends of said shafts, the pinions on corresponding ends of the shafts being disposed on opposite sides of the flange of one of said racks for meshing engagement with the rack portions thereof, a prime mover connected to each of said shafts for driving the shafts in opposite directions to cause the pinions engaging each of said racks to revolve in opposite directions for propelling the elevator either upwardly or downwardly in the elevator shaft, the other two walls of said elevator shaft having rails fixed thereto and extending longitudinally thereof, brackets sup-

ported on the elevator and externally thereof, and a rail engaging wheel journaled in each of said brackets, said wheels engaging said rails for guiding the elevator in its movement in the elevator shaft, each of said last mentioned elevator shaft walls being provided with two rails, said elevator being provided with two wheels engaging each of the rails, and each of said wheels having a flanged outer edge engaging the outer edge of the head of one of the rails for holding the elevator against lateral movement in any direction relatively to the elevator shaft.
